ATT'Y

UNITED STATES PATENT OFFICE.

JOHAN M. ANDERSEN, OF BOSTON, MASSACHUSETTS.

DESIGN FOR A BICYCLE-FRAME.

SPECIFICATION forming part of Design No. 27,618, dated August 31, 1897.

Application filed December 5, 1896. Serial No. 614,662. Term of patent 14 years.

To all whom it may concern:

Be it known that I, JOHAN M. ANDERSEN, of Boston, in the county of Suffolk and State of Massachusetts, have invented and produced a new and original Design for Bicycle-Frames, of which the following description, in connection with the accompanying drawing, is a specification, like letters on the drawing representing like parts.

10 The design relates to a bicycle-frame of that class known as "ladies'" bicycles; and it consists in a bicycle-frame distinguished by its peculiar shape, as will be hereinafter set forth and claimed.

15 The drawing represents in side elevation a bicycle-frame embodying this design.

The leading and distinctive feature of my design consists in the irregular seat-post composed of the straight upper portion a , the straight lower portion or tube-section a^2 in the same plane or line as the upper portion a , and the intermediate rearwardly-curved portion a' , extended rearwardly beyond the plane

of the portions a a^2 and forward beyond the plane of the parts a a^2 up to the head-post b^4 25 to form the inclined front bar b , having the curved lower portion b' integral with the curved portion a' of the seat-post, so that the head-post b^4 is connected to the inclined frame-rods b^5 by a single continuous tube 30 composed of converging inclined sections or parts a b , united by an enlarged curved portion a' . The head-post b^4 has extended from its lower end the inclined bar b^2 , which is joined to the crank-hanger a^3 , to which the 35 section a^2 of the seat-post is also joined.

I claim—

The design for a bicycle-frame herein shown and described.

In testimony whereof I have signed my 40 name to this specification in the presence of two subscribing witnesses.

JOHAN M. ANDERSEN.

Witnesses:

JAS. H. CHURCHILL,
J. MURPHY.
